FRED D. WACHSMUTH, OF SANFORD, TEXAS

CHECK VALVE FOR FLUID LIFTS

Application filed November 15, 1930. Serial No. 495,983.

This invention relates to fluid lifts especially adapted for use in flowing wells and contemplates the employment of a pressure fluid such as compressed air or gas to augment the natural pressure of the well in bringing about the ascent of the native well fluid to the surface.

More particularly, the invention contemplates novel means by which the packer that is located between the producing stratum and the lifting fluid employed to recover the native well fluid is expanded and set by the lifting fluid with the result that by cutting off or temporarily interrupting the supply of lifting fluid the packer is released and a convenient change in the position of the same is made possible, all without damage to the packer or other parts of the assembly.

Another attribute of the invention resides in the arrangement by which the check valve assembly that is located within the flowing conduit and which, of course, is employed to prevent retrograde movement of the native well fluid, may be easily withdrawn to the surface without the necessity of removing the flowing conduit along with it and which, during removal is held in open position to allow of the passage therethrough of such paraffin as may be encountered, it being noted in this connection that the collection of a substantial portion of paraffin above the check valve as an incident to the removal of the check valve might bind the check valve and prevent the ready removal of the same.

Another object is to provide a flowing device which is of highly simplified construction, which is reliable in use and which may be employed without a substantial departure from established producing methods.

Other objects and advantages will become apparent as the description proceeds.

In the accompanying drawing forming a part of this application and in which like numerals are employed to designate like parts throughout the same,

Figure 1 is a fragmentary vertical sectional view through the improved fluid lift, parts being broken away and the check valve assembly being shown in seated position.

Figure 2 is a similar view showing the

check valve assembly partly withdrawn and the valve element thereof open.

Figure 3 is a side elevation of the check valve assembly, parts being broken away.

In the drawing wherein for the purpose of illustration is shown a preferred embodiment of the invention, the numeral 5 designates a well casing which, of course, extends from the surface and which may be seated at the lower end thereof on the cap rock of the producing formation. 55 60

A flowing string of pipe or conduit 6 is located within the casing 5 in spaced relation to the inner side wall thereof to cooperate therewith in the formation of an annular passage by which a pressure or lifting fluid such as compressed air or gas may be introduced into the well and brought into lifting relation to the fluid products of the well. 95

The flowing device comprises, in part, a tubular body 8 upon which a suitable number of upwardly presented cups 10 are mounted, the lower cup or cups, as the case may be, being confined between followers 12, while the upper cup is confined between a jam nut 14 and the uppermost follower. 70 75

As shown in Figure 1, the cups 10 are adapted to establish a fluid tight contact between the casing 5 and the flowing conduit 6 to set up an effective barrier between the producing stratum and the pressure fluid located above, with the result that the pressure fluid is not allowed to throttle or interfere with the free admission of the native well fluid into the shot hole and the inlet to the flowing conduit. Since the cups are presented upwardly and are exposed to the pressure of the lifting fluid such as compressed air or gas, it is clear that the cups will be expanded thereby into fluid tight contact with the wall of the casing to protect the

with the wall of the casing to protect the producing stratum below from the restraining influence of the lifting fluid; and when the supply of pressure fluid at the surface is cut off the ready movement or adjustment of the packing devices 10 is made possible through movement of the flowing conduit, all without damage to the packing devices.

As shown in Figures 1 and 2, the packing body 8 has the upper portion thereof ex- 100

ternally enlarged and the bevelled shoulder defined by such enlargement is provided with an annular series of upwardly inclined ports or jets 16 extending entirely therethrough and providing a means by which the pressure medium such as compressed air or gas may be brought into lifting relation to the fluid being recovered. By reason of the upward inclination of the jets 16 and the fact that the same form a ring entirely surrounding the fluid being recovered, a diminished pressure will prevail within that portion of the body 8 below the jets and the column of fluid being recovered will be very much lightened.

A tubular section or check valve housing 20 is shown to be threaded onto and suspended from the packing body 8 and is adapted for the reception of a check valve assembly comprising a check valve body 22 upon which a plurality of upwardly presented cups 24 are mounted. Suitable means such as followers 26 and a jam nut 28 may be employed to hold the cups in position on the check valve body 22 to leave the outer edge portions thereof free for fluid tight contact with the wall of the tubular section 20. The check valve body is, of course, formed with a fluid passage extending entirely therethrough and is provided at the upper end thereof with an annular seat for engagement by a semispherical valve element 30. During the ascent of the native well fluid through the check valve body 22 the valve element 30 is, of course, unseated or in the raised position and when the ascent of the native well fluid ceases or is interrupted the valve element is seated to prevent retrograde movement of the fluid above. Obviously, the pressure of the fluid immediately above the cups 24 will aid in establishing fluid tight contact of these cups with the surrounding tubular section 20.

The lowermost follower 26 or other part associated with the check valve body 22 is provided with a plurality of flexible diverging depending spring arms 32 having the lower portions thereof bevelled inward for entrance into an annular groove defined by an internal annular rib 34 located in the lower portion of the housing 20 so that the descent of the check valve assembly is limited. In this manner, the seating of the cups or other packing devices 24 at the desired point within the housing 20 is assured. The inherent flexibility of the arms 32 provides a means by which the bevelled lower portions of the arms are caused to seat with certainty in the groove defined by the upwardly presented rib 34. On the other hand, when it is desired to unseat the check valve assembly no substantial resistance is offered by the arms 32.

As clearly illustrated in Figure 3, the valve element 30 is limited in its upward movement with respect to the seat thereof

by a dart 38 located below the valve body 22 and having connection with the valve element by a stem 40 that is extended entirely through the valve body. Thus, the connection of a lifting device 42 of any nature with the U-shaped bail 44 of the valve element 30 will provide a means by which the check valve assembly may be withdrawn to the surface with the valve element 30 in open position. As brought out in the opening paragraphs of this specification, by holding the valve element in an open position during the removal of the check valve assembly such paraffin as may be encountered is allowed to pass through the valve body 22 and is thus prevented from collecting in sufficient volume to bridge the flowing conduit and prevent the complete removal of the check valve assembly.

Therefore, the check valve assembly may be removed with the aid of the lifting device 42, of whatever nature it happens to be, and without the necessity of removing the flowing conduit. Such an arrangement is highly advantageous in wells where frequent or even occasional cleaning of the same is necessary because it avoids the necessity of removing the flowing conduit, such removal of the flowing conduit being known to be a time consuming task entailing a considerable labor cost and loss of production.

From the foregoing, it is believed to be clear that the introduction of a lifting fluid such, for example, as compressed air or gas into the space between the casing 5 and the flowing conduit will result in the passage of such lifting fluid into the flowing conduit and in the ascent of the native well fluid that has entered the flowing conduit.

The introduction of the pressure fluid into the casing will bring about the expansion of the cups 10 or other packing devices into fluid tight contact with the surrounding wall of the casing so that the pressure fluid is prevented from entering the producing stratum and retarding the free flow of native well fluid into the shot hole of the well. So long as the supply of pressure fluid to the space between the casing 5 and the flowing conduit is continued the packing devices 10 will remain in fluid tight contact with the casing and when such supply is cut off or interrupted the fluid tight contact of the members 10 with the wall of the casing is destroyed until such time as the supply of pressure fluid is renewed. During the time that the pressure fluid is not supplied to the casing it is a simple matter to move the cups or other packing devices 10 by movement of the flowing conduit.

It is obvious, that inlet means in addition to the openings 16 may be provided at various levels in the well to meet the exigencies of the case. It being noted in this connection that the same conditions seldom exist

in two wells and the location of the inlet means and, in fact, the entire recovery mechanism, is dictated by the conditions thought to exist in the well.

8 It is to be understood that the form of invention herewith shown and described is to be taken merely as a preferred example of the same and that such minor changes in arrangement and construction of parts may 10 be made as will remain within the spirit of the invention and the scope of what is claimed.

Having thus described the invention, what is claimed is:

15 1. In a check valve assembly for use in the fluid conduit of a well, a tubular body having a valve seat, a valve element to engage said seat and having a stem extending through the body, a dart carried by said stem 20 and adapted to engage the lower portion of said body to limit unseating of said valve element, packing devices on said body to engage the surrounding fluid conduit, and retaining means for said packing devices and 25 provided with an annular series of depending anchoring arms to engage the surrounding fluid conduit and being in protecting relation to said dart.

2. In a check valve assembly for use in 30 the fluid conduit of a well, a tubular body, a valve element carried by the tubular body, a stem extending through the tubular body and provided with a dart to engage the lower end of said body to limit unseating of said 35 valve, and a member carried by said body and being provided with an annular series of depending spring arms surrounding said dart to space the same from contact with the fluid conduit and being provided with 40 means to detachably anchor the check valve assembly in place.

In testimony whereof I affix my signature.

FRED D. WACHSMUTH.
